BOBBY PIN CARDING MACHINE

Ruth K. Weaver, Chicago, Loren M. Wingblade, Mount Prospect, and Lewis E. Thatcher, Berwyn, Ill., assignors to Gaylord Products, Incorporated, Chicago, Ill., a corporation of Delaware

Application October 21, 1948, Serial No. 55,722

15 Claims. (Cl. 163—8)

1

This invention relates to apparatus for mounting bobby pins upon cards for distribution and sale. During recent years it has been common practice for hairpin manufacturers to provide blanks of cardboard with apertures to receive bobby pins which were mounted in assembled relation upon the cards by hand. It is an object of the present invention to materially reduce cost of packaging bobby pins on cards by providing a machine adapted to accomplish this operation.

Patent No. 2,285,433 granted June 9, 1942, to Walter H. Hermsdorf discloses a device for threading hairpins or the like upon cards, and more particularly discloses a device adapted for use in bending a blank of cardboard adjacent the apertures therein to facilitate the mounting of bobby pins upon a card. The present invention contemplates the provision of a machine in which the bobby pins are adapted to be transferred directly from an oven wire onto apertured cards. The term "oven wire" refers to a rod upon which the bobby pins are mounted during manufacturing operations, such as heat treatment, japanning, varnishing, drying, etc., prior to removal for packaging and distribution to the public. As each oven wire is adapted to support approximately 70 or 80 bobby pins in spaced parallel relation, the present machine contemplates the provision of means for threading the pins from an oven wire onto three or more individual apertured cards.

This invention further contemplates the provision of a machine embodying means for dividing the bobby pins upon the oven wire into groups of predetermined number; after which, the groups of bobby pins are transferred from the oven wire onto their respective cards by threading one leg of each bobby pin through its respective aperture provided in the card.

This invention further contemplates the provision of improved means for delivering a group of cards from their respective hoppers into loading position adjacent the group of bobby pins mounted upon an oven wire, and means for bending the cards adjacent their apertures to facilitate insertion of the legs of the bobby pins therethrough during transfer of the bobby pins from the oven wire to the card.

This invention further contemplates the provision of means for stripping the oven wire from the bobby pins after the latter have been threaded onto the merchandising cards.

This invention embodies other novel features, details of construction and arrangement of parts which are hereinafter set forth in the specifica-

2

tion and claims and illustrated in the accompanying drawings, wherein:

Fig. 1 is a rear elevational view showing a carding machine embodying features of this invention.

Fig. 2 is a transverse sectional view taken along the line 2—2 of Fig. 1, showing the first stage in the operation in which a group of cards are lifted from the upper end of their respective hoppers for movement toward their loading positions.

Fig. 3 is a transverse sectional view corresponding to Fig. 2, showing a group of bobby pins loaded upon a card at the completion of the carding operation.

Fig. 4 is a transverse sectional view taken along the line 4—4 of Fig. 1.

Fig. 5 is a transverse sectional view taken along the line 5—5 of Fig. 1.

Fig. 6 is a transverse sectional view taken along the line 6—6 of Fig. 1.

Fig. 7 is an enlarged transverse sectional view, showing the position of the several parts of the mechanism immediately prior to threaded engagement of the bobby pins upon a card.

Fig. 8 is an enlarged detailed sectional view taken along the line 8—8 of Fig. 7.

Fig. 9 is an enlarged sectional view taken along the line 9—9 of Fig. 7.

Fig. 10 is a plan view showing a merchandising card slit to provide apertures to receive bobby pins.

Fig. 11 is a plan view showing the manner in which bobby pins are mounted in groups upon a merchandising card by means of the apparatus shown and hereinafter described.

Fig. 12 is a sectional view taken along the line 12—12 of Fig. 11.

Referring now to the drawings for a better understanding of this invention, and more particularly to Figs. 10, 11 and 12 therein, merchandising cards 4 formed of cardboard, or other flexible material, are provided with slits at 6 to receive groups of bobby pins 7. As illustrated in Figs. 11 and 12, one leg 8 of each bobby pin is threaded through a slit 6 with the crimped leg 9 disposed along the front side of the card. The slits 6 are preferably formed U-shape to provide a tab portion 11 to engage the loop end 12 of the bobby pins and hold same against outward displacement from the cards.

The machine for threading the bobby pins 7 onto the cards 4 is shown as comprising a plurality of hoppers 13 supported upon the frame 14 of the machine and adapted to receive stacks

of display cards 4. Each hopper 13 is of well-known construction, embodying a vertically movable platform 16 adapted to support the stack of cards 4 and to move upwardly responsive to rotational movement of a shaft 17 journaled in the frame 14 and actuated by a crank 18. The shaft 17 is provided with a pair of sprocket gears 16-19 keyed thereto for engagement with their respective sprocket chains 21-21, one end of said chains being secured to the supporting plates 16 and the other end of the chains being fastened to counterweights 22-22. The crank 18 is adapted to be engaged and rotated by any suitable mechanism (not shown) to maintain the upper cards in the hoppers at a predetermined level during the operation of the machine.

Card transfer mechanism

A card transfer mechanism for transferring cards 4 from their respective hoppers 13 to a loading position within the machine is shown as comprising a card transfer frame 23 which is keyed at its lower end to a shaft 24. An air conduit 26 is supported at the upper end of the frame 23 to receive a plurality of sucker fingers 27 provided at their ends with the usual flexible rubber nozzles 28. A flexible air conduit 29 leads from the air conduit 26 to a valve 31 supported upon the side of the frame 14.

The shaft 24 is journaled at its ends in bearing apertures formed at the outer ends of a pair of arms 32 which have their inner ends keyed to a shaft 33 journaled on the frame 14. A cam actuating arm 34 is keyed at its inner end to the shaft 33 and carries a roller 36 at its outer end for engagement by a cam 37 keyed to a shaft 38. The shaft 38 is journaled at its ends in suitable bearings provided in the machine frame 14 and is rotated in a clockwise direction, as illustrated in Figs. 2, 3 and 4 by means of a pulley 39 and drive belts 41 leading to the pulley of an electric motor or other suitable source of power 40. As illustrated in Figs. 2, 3 and 4 of the drawings, rotational movement of the cam 37 acts through the arm 34, shaft 33, arm 32 and shaft 24 to alternately raise and lower the card transfer frame 23 to bring the sucker fingers 27 into and out of engagement with the cards 4 in the hoppers 13.

An actuating arm 42 is keyed at its inner end to the shaft 24 and provided at its outer end with a roller 43 for engagement against a cam 44 keyed to the shaft 38. During rotational movement of the shaft 38, the cam 44 acts through the arm 42 and shaft 24 to pivot the card transfer frame 23 between its card pick-up position and its card delivering position. The roller 43 is held in engagement with the cam 44 by means of a tension spring 46 having its one end connected with the frame 14 and its other end connected to the free end of the arm 42.

Bobby pin grouping mechanism

As illustrated in Figs. 2, 7, 8 and 9 in the drawings, bobby pins 7 are mounted in spaced parallel alignment along an oven wire 47 having its ends offset laterally in spaced parallel relation at 48-48 and thence bent outwardly at 49-49. The oven wire 47, with the bobby pins 7 mounted thereon, is mounted upon a bobby pin grouping mechanism indicated generally at 50. The grouping mechanism 50 comprises a pair of side members 51-51 mounted for reciprocatory movement in bearings 52 bolted to the frame 14. Each side member 51 is provided with a roller 53 for

engagement with a cam 54 keyed to the shaft 38. Each roller 53 is held in engagement with its respective cam 54 by means of a flexible cable 55 having its one end connected to its side member 51 and its other end connected to one end of a tension spring 57 secured to the machine frame 14. A fork supporting bar 58 is journaled at its ends in the end members 51 and has a worm gear 59 keyed thereon for engagement by a worm 61. The worm 61 is journaled in bearings 62-62 provided on one of the end arms 51 and is manually rotated by means of the handle 63.

A pair of fork members 64 and 66 are secured in spaced parallel relation on the fork supporting bar 58, the outer free ends of the fork members being formed with similar wedge-shape teeth 67 which serve to move the bobby pins 7 into groups of predetermined number along the oven wire 47. The oven wire 47, with the bobby pins mounted thereon, is manually positioned upon the ends of the fork members 64 and 66, as illustrated in Fig. 2 in the drawings, when the fork supporting bar 58 is in its raised position. The oven wire 47 is held against outward displacement from the ends of the fork members 64 and 66 by means of a pair of flat resilient spring members 68-68 having their one ends secured to the fork supporting bar 58 and their free ends formed with offset portions 69.

As illustrated in Figs. 8 and 9, a pair of oven wire retainer strips 71-71 formed of flat resilient metal with their outer end portions projecting downwardly are secured at their outer ends to the frame 14 and have their inner ends inclined upwardly and outwardly at 72. A pair of actuating arms 73-73 are secured to the fork supporting bar 58 to prevent cocking movement of the oven wire when the latter engages the inclined portions 72-72 of their respective strips 71-71 in order to move the strips 71-71 away from each other during inward movement of the bobby pin grouping mechanism 50. When the grouping mechanism 50 reaches the inner end of its stroke, the oven wire 47 is engaged against plates 74-74 provided on the machine frame 14. Prior to upward return movement of the grouping mechanism 50, the retainer strips 71-71 move inwardly toward each other and hold the oven wire 47 in fixed position against the plates 74-74.

Front card holder mechanism

The machine is provided with a front card holder mechanism, generally indicated at 76, and a rear card holder mechanism, generally indicated at 77. The front card holder mechanism 76 comprises a pair of arms 78-78 journaled at their inner ends upon a tubular member 79 enclosing the shaft 38, the outer ends of the arms 78-78 being connected to each other by means of a cross frame 81. A clamping plate holder 82 is keyed to a cross shaft 83 which has its ends journaled in the cross frame 81. A cam arm 84 is keyed to one end of the shaft 83 for engagement against a pin 86 projecting outwardly from one side of the machine frame 14 when the front card holder mechanism is in its loading position, as illustrated in Fig. 2 in the drawings. A card clamping plate 87 and a flat resilient spring member 88 are secured at their one ends to the plate holder 82 by means of suitable screws and normally rest in line engagement with each other when the front card holder mechanism is moved away from its card loading position.

When the front and rear card holder mechanisms 76 and 77 are in their loading positions, illustrated in Fig. 2, the free end of the resilient spring member 88 is engaged under the card receiving plate 89 provided on the rear card holder mechanism 77, and the pin 86 acts against the cam arm 84 to rotate the plate holder 82 and thus move the clamping plate 87 away from the spring member 88 and to define therewith an inwardly converging recess to receive a card 4. A tension spring 91 is connected at its one end to the cross frame 81 and at its other end to a pin 92 mounted on the plate holder 82. The spring 91 normally acts to rotate the plate holder 82 to maintain the plate 87 in line engagement against the spring member 88 which, in turn, is held against a block of resilient rubber 94 mounted on the cross frame 81.

Rear card holder mechanism

The rear card holder mechanism 77 is shown as comprising a pair of side arms 96-96 journaled at their inner ends for pivotal movement about the shaft 79 and having their outer ends connected by a transverse member 97 which supports the plate 89.

A card clamping frame, generally indicated at 101, is mounted for reciprocatory movement on the rear card holder mechanism 77 for movement into and out of card clamping engagement with the plate 89. The card clamping frame 101 comprises a hold-down bar 102 mounted at its ends upon a pair of plungers 103-103 guided for reciprocable movement in guide slots 104-104 provided on the arms 96-96. A pair of compression springs 106-106 are provided on the arms 96-96 to engage pins 107-107 mounted on the plungers 103-103. The compression springs 106-106 normally act to hold the hold-down bar 102 in card clamping engagement against the plate 89. A bobby pin guiding plate 108 formed with a plurality of guide slots 109 to receive groups of bobby pins, is supported upon the card clamping frame 101 by means of resilient strip members 111. Several resilient spring guide members 112 are also supported upon the card clamping frame 101 to serve in guiding the cards 4 into loading position upon the plate 89.

Actuating means for front and rear card holder mechanisms

A pair of cams 116-116 are keyed in spaced relation to the drive tube 79 adjacent the arms 96-96 of the rear card holder mechanism. The outer surface of each cam 116-116 is slotted at 117 to receive a roller 118 during counterclockwise rotation of the cams. The rollers 118-118 are journaled on pins provided on plungers 103-103, as illustrated in Fig. 8. The cams 116-116 are also provided with push plates 119-119 for engagement against pins 121-121 provided on the arms 78-78 of the front card holder mechanism. Return push plates 122-122 are also mounted on the cams 116-116 for engagement with the abutment pins 121-121 provided on the arms 78-78.

The rear card holder mechanism is pivotally movable between front stop members 123-123 and rear stop members 124-124 provided on the frame 14. Adjustable push lugs 126-126 are provided on the plate supporting frame 81 of the front card holder mechanism for engagement by the arms 96-96 of the rear card holder mechanism.

A pair of cables 127-127 are connected at their one ends to the arms 96-96 of the rear card holder mechanism and are connected at their other ends to tension springs 128-128 secured to the frame 14. Idler pulleys 129-129 are journaled on the frame 14 to receive and guide the cables 127-127.

A pair of cables 131-131 are connected at their one ends to the arms 79-78 of the front card holder mechanism and are connected at their other ends to counterweights 132-132 movable along guide plates 133-133. Idler pulleys 134-134 are journaled on the arms 96-96 of the rear card holder mechanism to guide the cables 131-131.

A gear 136 is keyed to the drive tube 79 for meshing engagement with a gear segment 137 journaled on a stud shaft 138 provided on the frame 14. A cam roller 139 is journaled on the gear segment 137 for movement along a cam track 141 formed in a box cam 142 keyed to the shaft 38. A brake shoe 143 is mounted for pivotal movement on a pin 144 provided on the machine frame 14 and is normally held in frictional braking engagement with the periphery of the box cam 142 by means of a compression spring 146.

A cross bar 151 is supported at its ends in brackets 152 provided on the machine frame 14. A plurality of abutment fingers 153 are pivotally connected at their inner ends upon a rod 154 which is supported upon the cross bar 151. The free ends of the abutment fingers 153 are formed with abutment shoulders 156 for engagement against the loop ends 12 of the bobby pins 7, as illustrated in Fig. 7. Each abutment finger 153 is provided with an arm 157 for engagement by a compression spring 158 mounted upon a stud 159 provided on the cross bar 151. The compression springs 158 serve to yieldably resist upward movement of the abutment fingers 153.

An aluminum plate 161 is supported on one side of the cross bar 151 to coact with a permanent magnet 162 secured on the end of an arm 163, the inner end of the arm 163 being secured to a shaft 164 journaled in brackets 166-166 provided on the cross bar 151. An operating handle 167 is secured on one end of the shaft 164 to move the permanent magnet 162 out of engagement with the aluminum plate 161. The permanent magnet 162 is held in engagement with the aluminum plate 161 by means of an arm 168 secured to the shaft 164 and engaged by a tension spring 169 secured to the frame 14.

An actuating arm 171 is keyed to the shaft 83 of the front card holder mechanism 76 for engagement by a cam segment 172, when the front card holder 76 approaches its forward position, to cause the plate 87 to move outwardly relative to the spring member 88.

Operation

In the operation of the machine for mounting bobby pins 7 upon flexible blanks of cardboard 4, an oven wire 47, loaded with 70 or 80 bobby pins, is first manually positioned upon the fork members 64 and 66 in the manner illustrated in Fig. 2 in the drawings, the resilient spring member 68 serving to hold the oven wire against outward displacement from the fork members. The operator then rotates the handle 63 which acts through the worm 61 and worm gear 59 to move the fork members into parallel alignment with the arms 51. An adjustable abutment screw 176

is provided on the bearing flange 62 to limit the downward movement of the fork members 64 and 66.

The arms 51—51 carrying the fork members 64 and 66 are caused to move inwardly during rotational movement of the cam 54 by the action of the tension springs 57—57 and cables 56—56. During inward movement of the fork members 64 and 66, the bobby pins 7 are arranged in groups, as illustrated in Fig. 9, by means of the wedge-shape prongs 67 formed on the fork members. During inward movement of the bobby pin grouping mechanism 59, the plates 73—73 provided on the fork supporting bar 58 act to prevent cocking movement of the oven wire 47 when the latter engages against the inclined end portions 72—72 of the spring members 71—71 to move the latter away from each other a sufficient distance to permit the offset portions 48—48 of the oven wire 47 to come to rest against the plates 74—74. During outward movement of the bobby pin grouping mechanism 59, the spring plates 71—71 move into engagement over the upper sides of the offset portions 48—48 of the oven wire 47, causing the latter to be stripped from the fork members 64 and 66.

The cards 4 are transferred from their respective hoppers 13 to the front and rear card holders 76 and 77 by means of the card transfer mechanism which includes a frame 23 and sucker fingers 27 mounted thereon. The sucker fingers 27 are moved into and out of engagement with the cards 4 and the hoppers 13 by means of the cam 37 which acts through the arms 34 and 32 to raise and lower the frame 23. The frame 23 is movable back and forth between the hoppers 13 and the front and rear card holders 76 and 77 by means of the cam 48 which acts through the arm 42 and shaft 24 to pivot the frame 23. When the sucker fingers 27 are moved into engagement with the cards 4 in the hoppers 13, a vacuum condition is created within the sucker fingers and the conduits leading thereto by means of a cam 177 keyed to the shaft 32 to operate the plunger 178 of the valve 31. The valve 31 is connected to a suitable vacuum tank by means of a conduit 179. When the cards 4 are moved to their forward position by means of the card transfer mechanism, the vacuum to the sucker fingers 27 is broken by the action of the cam 177 to permit the cards 4 to fall downwardly by gravity onto the front and rear card holder mechanisms 76 and 77.

After the cards 4 are mounted upon the front and rear card holders 76 and 77, the notches 117—117 on the cams 116—116 are moved into registry with the rollers 118—118 provided on the plungers 103—103. Movement of the rollers 118—118 out of their respective notches 117—117 is yieldably resisted by means of the compression springs 106—106 interposed between the upper portions of the arms 96—96 and the plungers 103—103, as illustrated in Fig. 8.

When the rollers 118—118 move into their respective notches 117—117, the plungers 103—103 act to draw the cross bar 102 inwardly into clamping engagement against the plate 88 mounted upon the transverse member 97 which extends between and is connected to the outer ends of the arms 96—96.

When the rollers 118—118 drop into the recesses 117—117 during counterclockwise rotation of the cams 116—116, as illustrated in Figs. 2 and 7, the cams 116—116 then act to move the rear card holder mechanism 77 toward the front card

holder mechanism 76, causing the cards 4 to buckle intermediate their ends and adjacent the slits 6 to facilitate insertion of the lower legs of the bobby pins through the slits. After the rear card holder has travelled a sufficient distance to buckle the cards 4, the stop pins 125—125 on the arms 96—96 engage against the adjustable screws 126—126 provided on the front card holder to push the latter in a counterclockwise direction. Immediately upon movement of the front card holder in a counterclockwise direction, as illustrated in Fig. 2, the cam arm 84 moves out of engagement with the pin 86 to permit the tension spring 91 to rotate the plate holder 82 to bring the plate 87 into clamping engagement with the spring member 88 to clamp the cards 4 therebetween in the manner illustrated in Fig. 7. The front and rear card holders 76 and 77 then move as a unit in a counterclockwise direction to cause the cards 4 to move relative to the bobby pins 7 mounted on the oven wire 47. During movement of the cards 4 relative to the bobby pins 7, the groups of bobby pins are directed toward their respective card slits 6 by means of the guide grooves 109 formed in the guide bar 108, causing the lower uncrimped legs of the bobby pins to be threaded through the slots 6 and the upper crimped legs to be disposed against the outer face of the cards. The pusher fingers 153 serve to hold the groups of bobby pins in fixed position until they are mounted upon the cards 4 in the manner illustrated in Fig. 11; after which, the bobby pins 7 force the fingers 153 upwardly against the action of the compression spring 152.

After the bobby pins have been mounted upon the cards 4, the rear card holder mechanism 77 is brought to rest against the adjustable stop members 123—123 causing the cams 116—116 to force the rollers 118—118 out of their recesses 117—117 and thus move the clamping bar 102 out of clamping engagement with the plate 89 to release the cards from the rear card holder 77.

After release of the cards 4 from the rear card holder 77, the front card holder 76 is caused to continue its movement in a counterclockwise direction by engagement of the push lugs 119—119 against the abutment pins 121—121 provided on the arms 96—96. During downward movement of the front card holder 76 and near the end of its movement, cam arm 171 moves into engagement with the cam segment 172, illustrated in Fig. 5, to cause rotational movement of the shaft 23 to cause the plate 87 to move out of clamping engagement with the spring 88. As the plate 87 moves away from the spring plate 88, the permanent magnet 162 acts to draw and hold the bobby pins and card against the aluminum plate 161 until the card has passed from between the plate 87 and spring plate 88. The lever 167 is then moved in a counterclockwise direction as illustrated in Fig. 5 to rotate the shaft 164 and to move the magnet 162 away from the aluminum plate 161 to cause the loaded card of bobby pins to drop into a hopper 191. It is contemplated that the lever 167 may be either manually or automatically operated to move the magnet 162 away from the plate 161.

During movement of the roller 139, on the gear segment 137, along the cam track 141 of the box cam 142, the front card holder 76 is brought to rest in its lower position and then moved upwardly toward its first position by means of the push lugs 122—122 provided on the cams 116—116. As illustrated in Figs. 2 and 3,

the push lugs 122—122 engage against the abutment studs 121—121 to move the front card holder in a clockwise direction. During clockwise movement of the front card holder 76 the adjustment screws 126—126 thereon engage and move the rear card holder 77 in a clockwise direction until the latter is brought to rest by engagement of the stop pins 125—125 against the abutment 124—124. Immediately prior to the termination of the movement of the front card holder 76 in a clockwise direction, the arm 84, keyed to the shaft 83, engages against the stop pin 86 to move the plate 87 away from the plate 88. It will be noted that the forward end of the spring plate 88 is engaged under one end of the plate 89 during opening movement of the plate 87.

While this invention has been shown in but one form, it is obvious to those skilled in the art that it is not so limited but is susceptible of various changes and modifications without departing from the spirit and scope of the claimed invention.

We claim as our invention:

1. In a machine for transferring bobby pins from an oven wire onto flexible cards formed with bobby pin receiving apertures, a frame, a front card holder mechanism mounted for movement on said frame to receive and clamp one end of a flexible card, a rear card holder mechanism mounted on said frame to receive and clamp the other end of the flexible card, means to support an oven wire carrying a plurality of bobby pins disposed in a common plane, common means to move said front and rear card holder mechanisms relative to said oven wire supporting means to cause one leg of each bobby pin to pass through the apertures of said flexible card and then to strip the bobby pins from the oven wire, abutment fingers mounted on said frame to engage the loop ends of the bobby pins to yieldably resist displacement of said bobby pins from the oven wire while the legs of the bobby pins are being inserted through the apertures in said flexible cards, and means operable to disengage and remove a flexible card with bobby pins thereon from said front and rear card holder mechanisms.

2. In a machine for transferring bobby pins from an oven wire onto flexible cards formed with bobby pin receiving apertures, a frame, a front card holder mechanism mounted for movement on said frame to receive and clamp one end of a flexible card, a rear card holder mechanism mounted on said frame to receive and clamp the other end of the flexible card, means to support an oven wire carrying a plurality of bobby pins disposed in a common plane, common means to move said front and rear card holder mechanisms relative to said oven wire supporting means to cause one leg of each bobby pin to pass through the apertures of said flexible card and then to strip the bobby pins from the oven wire, abutment fingers mounted on said frame to engage the loop ends of the bobby pins to yieldably resist displacement of said bobby pins from the oven wire while the legs of the bobby pins are being inserted through the apertures in said flexible cards, means operable to disengage and remove a flexible card with bobby pins thereon from said front and rear card holder mechanisms, and means to move said bobby pins along said oven wire to form spaced groups of abutting bobby pins.

3. In a machine for transferring bobby pins

from an oven wire onto flexible cards formed with bobby pin receiving apertures, a frame, a front card holder mechanism mounted for movement on said frame to receive and clamp one end of a flexible card, a rear card holder mechanism mounted on said frame to receive and clamp the other end of the flexible card, means to support an oven wire carrying a plurality of bobby pins disposed in a common plane, common means to move said front and rear card holder mechanisms relative to said oven wire supporting means to cause one leg of each bobby pin to pass through the apertures of said flexible card and then to strip the bobby pins from the oven wire, abutment fingers mounted on said frame to engage the loop ends of the bobby pins to yieldably resist displacement of said bobby pins from the oven wire while the legs of the bobby pins are being inserted through the apertures in said flexible cards, means operable to disengage and remove a flexible card with bobby pins thereon from said front and rear card holder mechanisms, and means to move said bobby pins along said oven wire to form spaced groups of abutting bobby pins.

4. In a machine for transferring bobby pins from an oven wire onto flexible cards formed with bobby pin receiving apertures, a frame, a front card holder mechanism mounted for movement on said frame to receive and clamp one end of a flexible card, a rear card holder mechanism mounted on said frame to receive and clamp the other end of the flexible card, means to support an oven wire carrying a plurality of bobby pins disposed in a common plane, common means to move said front and rear card holder mechanisms relative to said oven wire supporting means to cause one leg of each bobby pin to pass through the apertures of said flexible card and then to strip the bobby pins from the oven wire, abutment fingers mounted on said frame to engage the loop ends of the bobby pins to yieldably resist displacement of said bobby pins from the oven wire while the legs of the bobby pins are being inserted through the apertures in said flexible cards, means operable to disengage and remove a flexible card with bobby pins thereon from said front and rear card holder mechanisms, means to move said bobby pins along said oven wire to form spaced groups of abutting bobby pins, said last mentioned means including a fork member formed with wedge-shaped teeth movable in a plane normal to the oven wire to further move bobby pins along the oven wire to form groups of abutting bobby pins, and means to actuate said fork member relative to said oven wire prior to movement of said card holder mechanisms.

5. In a machine for transferring bobby pins from an oven wire onto a flat flexible card formed with bobby pin receiving apertures, a frame, support means on said frame to engage the ends of an oven wire having bobby pins mounted thereon, a front card holder mechanism mounted for movement on said frame past an oven wire engaged by said support means and including jaw means to grip the front end of a card, a rear card holder mechanism mounted for movement on said frame past said engaged oven wire and including jaw means to grip the rear end of a

card, and means to move said front and rear mechanisms with a card thereon past the engaged oven wire to transfer bobby pins from the wire onto the card.

6. In a machine for transferring bobby pins from an oven wire onto a flat flexible card formed with bobby pin receiving apertures, a frame, support means on said frame to engage the ends of an oven wire having bobby pins mounted thereon, a front card holder mechanism mounted for movement on said frame past an oven wire engaged by said support means and including jaw means to grip the front end of a card, a rear card holder mechanism mounted for movement on said frame past said engaged oven wire and including jaw means to grip the rear end of a card, means to move said front and rear mechanisms with a card thereon past the engaged oven wire to transfer bobby pins from the wire onto the card, and guide means mounted on said rear card holder mechanism to engage and direct the bobby pins onto said cards.

7. In a machine for transferring bobby pins from an oven wire onto a flat flexible card formed with bobby pin receiving apertures, a frame, support means on said frame to engage the ends of an oven wire having bobby pins mounted thereon, a front card holder mechanism mounted for movement on said frame past an oven wire engaged by said support means and including jaw means to grip the front end of a card, a rear card holder mechanism mounted for movement on said frame past said engaged oven wire and including jaw means to grip the rear end of a card, means to move said front and rear mechanisms with a card thereon past the engaged oven wire to transfer bobby pins from the wire onto the card, guide means mounted on said rear card holder mechanism to engage and direct the bobby pins onto said cards, and abutment fingers mounted on said frame to engage and yieldably resist displacement of the bobby pins from the oven wire during transfer of the pins from the oven wire to the cards.

8. In a machine for transferring bobby pins from an oven wire onto a flat flexible card formed with bobby pin receiving apertures, a frame, support means on said frame to engage the ends of an oven wire having bobby pins mounted thereon, a front card holder mechanism mounted for movement on said frame past an oven wire engaged by said support means and including jaw means to grip the front end of a card, a rear card holder mechanism mounted for movement on said frame past said engaged oven wire and including jaw means to grip the rear end of a card, means to move said front and rear mechanisms with a card thereon past the engaged oven wire to transfer bobby pins from the wire onto the card, guide means mounted on said rear card holder mechanism to engage and direct the bobby pins onto said cards, abutment fingers mounted on said frame to engage and yieldably resist displacement of the bobby pins from the oven wire during transfer of the pins from the oven wire to the cards, and means to remove a card with bobby pins thereon from said front and rear card holder mechanisms.

9. In a machine for transferring bobby pins from an oven wire onto a flat flexible card formed with bobby pin receiving apertures, a frame, support means on said frame to engage the ends of an oven wire having bobby pins mounted thereon, a front card holder mechanism mounted for movement on said frame past an oven wire engaged by said support means and including jaw

engaged by said support means and including jaw means to grip the front end of a card, a rear card holder mechanism mounted for movement on said frame past said engaged oven wire and including jaw means to grip the rear end of a card, means to move said front and rear mechanisms with a card thereon past the engaged oven wire to transfer bobby pins from the wire onto the card, the front jaw means and rear jaw means being disposed in offset relation to buckle the card adjacent the apertures therein to facilitate mounting of bobby pins on the card.

10. In a machine for transferring bobby pins from an oven wire onto a flat flexible card formed with bobby pin receiving apertures, a frame, support means on said frame to engage the ends of an oven wire having bobby pins mounted thereon, a front card holder mechanism mounted for movement on said frame past an oven wire engaged by said support means and including jaw means to grip the front end of a card, a rear card holder mechanism mounted for movement on said frame past said engaged oven wire and including jaw means to grip the rear end of a card, means to move said front and rear mechanisms with a card thereon past the engaged oven wire to transfer bobby pins from the wire onto the card, means to open said front and rear jaw means to release a card of bobby pins therefrom, and means to remove the card of bobby pins from said jaw means.

11. In a machine for transferring bobby pins from an oven wire onto a flat flexible card formed with bobby pin receiving apertures, a frame, support means on said frame to engage the ends of an oven wire having bobby pins mounted thereon, a front card holder mechanism mounted for movement on said frame past an oven wire engaged by said support means and including jaw means to grip the front end of a card, a rear card holder mechanism mounted for movement on said frame past said engaged oven wire and including jaw means to grip the rear end of a card, means to move said front and rear mechanisms with a card thereon past the engaged oven wire to transfer bobby pins from the wire onto the card, and means including a fork member having wedge-shape teeth to arrange the bobby pins into groups.

12. In a machine for transferring bobby pins from an oven wire onto a flat flexible card formed with bobby pin receiving apertures, a frame, support means on said frame to engage the ends of an oven wire having bobby pins mounted thereon, a front card holder mechanism mounted for movement on said frame past an oven wire engaged by said support means and including jaw means to grip the front end of a card, a rear card holder mechanism mounted for movement on said frame past said engaged oven wire and including jaw means to grip the rear end of a card, means to move said front and rear mechanisms with a card thereon past the engaged oven wire to transfer bobby pins from the wire onto the card, means including a fork member having wedge-shape teeth to arrange the bobby pins into groups, and means to move said fork member toward and away from said oven wire.

13. In a machine for transferring bobby pins from an oven wire onto a flat flexible card formed with bobby pin receiving apertures, a frame, support means on said frame to engage the ends of an oven wire having bobby pins mounted thereon, a front card holder mechanism mounted for movement on said frame past an oven wire engaged by said support means and including jaw means to grip the front end of a card, a rear card

holder mechanism mounted for movement on said frame past said engaged oven wire and including jaw means to grip the rear end of a card, means to move said front and rear mechanisms with a card thereon past the engaged oven wire to transfer bobby pins from the wire onto the card, and means including a shaft to support said front and rear card holder mechanisms for pivotal movement about a common axis.

14. In a machine for transferring bobby pins from an oven wire onto a flat flexible card formed with bobby pin receiving apertures, a frame, support means on said frame to engage the ends of an oven wire having bobby pins mounted thereon, a front card holder mechanism mounted for movement on said frame past an oven wire engaged by said support means and including jaw means to grip the front end of a card, a rear card holder mechanism mounted for movement on said frame past said engaged oven wire and including jaw means to grip the rear end of a card, means to move said front and rear mechanisms with a card thereon past the engaged oven wire to transfer bobby pins from the wire onto the card, and means to deliver a card to said front and rear jaw means for movement past said engaged oven wire.

15. In a machine for transferring bobby pins from an oven wire onto a flat flexible card formed with bobby pin receiving apertures, a frame, support means on said frame to engage the ends
